UNITED STATES PATENT OFFICE.

JOHN A. JOHNSON, OF MADISON, WISCONSIN.

MOLD-BOARD FOR PLOWS.

SPECIFICATION forming part of Letters Patent No. 390,480, dated October 2, 1888.

Application filed May 7, 1888. Serial No. 273,113. (No model.)

To all whom it may concern:

Be it known that I, JOHN A. JOHNSON, a citizen of the United States, and a resident of Madison, in the county of Dane and State of Wisconsin, have invented certain new and useful Improvements in Mold-Boards for Plows; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of the inner side of my improved mold-board for plows. Fig. 2 is a similar view of the re-enforcing frame detached from the mold-board proper, and Fig. 3 is a cross-section of my improved mold-board.

Like letters of reference denote corresponding parts in the several figures.

This invention has relation to an improved construction of the mold-boards of plows, and has for its object to increase the strength, durability, and wearing qualities of the board without at the same time unduly increasing its weight or the cost of manufacture.

To this end it consists in providing the mold-board on its inner side with a re-enforcing frame made of steel or iron and fastened to the inside of the mold-board around the edge of the same, substantially as will be hereinafter more fully described and claimed.

In the accompanying drawings, the letter A designates the mold-board, which may be of any suitable size or shape, according to the particular class of plows for which it is intended. This mold-board is made of a thin plate of steel, in the usual manner. To the inner side of the board is securely fastened a frame, B, made of steel or iron, and of any suitable thickness and width, said frame being of the same size and outline as the mold-board proper, so as to fit closely upon the same on the inside.

By providing the mold-board with a re-enforcing frame in the manner described I provide against accidental breakage of the board by

striking against obstructions, besides greatly increasing the wearing qualities of the board by making the edges of the same, where the wear comes, about twice the thickness of the middle part of the board, which has to sustain comparatively little wear. By my improvement the mold-board proper may be cut and shaped from flat plates of steel without requiring particular rolls or molds for shaping it; and, again, by making the thickness of the re-enforcing frame greater at the point of the mold-board I may still further re-enforce or strengthen that part of the mold-board.

I am well aware that it is not new in the manufacture of mold-boards for plows to roll them in such a manner that the edges, or parts where the greatest wear comes, shall be thicker and heavier than the middle part; and I am also aware that prior to my improvement so-called compound mold-boards have been made, consisting partly of iron and partly of steel; but both of these constructions involve the use of special machinery. By my improvement, on the other hand, the mold-board proper may be cut and shaped from ordinary plates of commercial steel without the use of complicated and expensive machinery, and the re-enforcing frame can be made and secured upon the mold-board proper by any artisan of ordinary skill, and without the use of machinery of any kind.

Having thus described my improvement, I claim, and desire to secure by Letters Patent of the United States—

The combination, with a mold-board for plows, consisting of a plate of even texture and thickness, of a re-enforcing frame corresponding in outline to the outline of the mold-board plate and permanently fastened to the same along its inner edge, substantially as and for the purpose herein shown and set forth.

In testimony that I claim the foregoing as my own I have hereunto affixed my signature in presence of two witnesses.

JOHN A. JOHNSON.
